UNITED STATES PATENT OFFICE.

FRANK KARÁCSONYI, OF YONKERS, NEW YORK, ASSIGNOR OF ONE-THIRD TO
GERGELY BLAGA, OF HASTINGS-UPON-HUDSON, NEW YORK.

DOOR-LOCK.

1,106,223.

Specification of Letters Patent.

Patented Aug. 4, 1914.

Application filed January 16, 1914. Serial No. 812,451.

To all whom it may concern:

Be it known that I, FRANK KARÁCSONYI, a subject of the King of Hungary, residing at Yonkers, in the county of Westchester 5 and State of New York, have invented certain new and useful Improvements in Door- Locks, of which the following is a specification.

This invention relates to certain new and 10 useful improvements in door locks, and has for its object the provision of novel and effective means for securing the locking bolt against being moved to an unlocked position by use of a key inserted in the lock from the 15 outside thereof.

A further object of the invention is to provide a door lock in which the lock bolt is secured against turning without manipulation of the knob shaft controlling the operation of the door latch.

With the above and other objects in view as will appear in the further description of the invention, the invention resides in the novel construction, combination and arrangement of parts to be hereinafter more fully pointed out and then claimed, and in describing the invention in detail, reference will be had to the accompanying drawing forming a part of this specification and 30 wherein like numerals of reference will be employed to designate like parts throughout the different views of the drawings in which:—

Figure 1 is a sectional elevation taken on 35 the line 1—1 of Fig. 3. Fig. 2 is a vertical sectional view showing the lock mechanism in side elevation, and, Fig. 3 is a transverse vertical sectional view taken on the line 3—3 of Fig. 2.

To put my invention into practice, I provide a lock casing 5 of the usual form, provided with an escutcheon plate 6, which casing 5 is adapted to be mortised into the door in the usual manner. In the lock casing 5 45 near the upper side thereof is arranged a keeper or housing 7 in which the latch bolt 8 is mounted, said latch bolt being pivotally connected at 9 to an arm 10 carried by the knob shaft 11 which as usual, is provided on 50 each end with a knob 12.

In the rear of the lock casing 5 is mounted a bracket 14, to which is secured one end of a bowed spring 15, the bow of said spring resting against the arm 10 and normally 55 holding the door latch 8 in its projected po-

sition. The other end of said bowed spring 15 bears against an arm 16 carried by a dog 17 that is pivotally-mounted as at 18 in the lower end of the bracket 14. The lock bolt 19 is slidably-mounted in the lower portion 60 of the casing 5, and is provided on its upper edge with a series of teeth 20, to coöperate with the tooth 21 of the dog 17.

Journaled in the lock casing 5 transversely thereof is a sleeve 22 which is extended at 65 one end beyond the lock casing and beyond the inner face of the door 23 to which the lock is applied. On said extended end this sleeve is provided with a suitable handle or knob 24, and adjacent the inner face of the door 23 is provided with oppositely-disposed apertures 25, 26, respectively, with one or the other of which the tooth 27 of a latch dog 28 is adapted to be engaged, said latch dog 28 being pivotally secured to the inner face 70 of said door 23 adjacent the shaft 22. In the inner end of said sleeve 22 is a squared shaft 29, on which is mounted a toothed wheel 30 that meshes with the teeth 20 of the lock bolt 19, the squared shaft 29 projecting beyond the said wheel 30 so as to form a projection which receives the socket end 31 of a key 32. The sleeve or hollow shaft 22, wheel 30 and shaft 29 rotate in unison, and may be operated by a handle 24 or a key 32. 85 A bushing 33 journaled in one of the side walls of the casing 5 and in a supporting plate 34 constitutes a bearing in which the inner end of the key 32 rotates.

With the latch dog 28 engaged with opening 90 26 as shown in Figs. 1 and 3, the lock bolt is held securely against turning by the key, so that the door, when the latch dog 28 is engaged, cannot be unlocked by the key. With the latch dog 28 raised out of engagement 95 with opening 26, the lock bar 19 is still held against retraction by means of the key, by reason of the tooth 21 of dog 17 being engaged with the teeth of said lock bolt 19. To release the lock bolt, after latch dog 28 100 has been released, it is necessary to turn knob 12, which causes arm 10 in its rearward movement to cause spring 15 to push against arm 16 of the dog 17, which retracts the tooth of the latter from the teeth of the lock bar, so that said lock bar may be retracted rearwardly by means of the key 32. In case it is desired to hold the lock bar 19 in the retracted position, the sleeve or hollow shaft 22 is turned so that lock dog 28 110

can be engaged with aperture 25, which will hold the lock bar in the retracted position.

What I claim as new is—

In a door lock, a casing, a lock bar slidably mounted in the casing, and provided with teeth on its upper edge, a hollow shaft journaled in the casing, a toothed wheel mounted on said shaft and engaging the teeth of said lock-bar, a dog pivoted on the 10 outside of the casing and adapted to engage an opening in said hollow shaft, a pivoted dog within the casing engaging the lock bar and provided with an angularly-pro-

jecting arm, a latch-bar, a knob-shaft connected with the latch bar by a swinging arm 15 on said knob-shaft, and means for releasing said dog from the lock-bar simultaneously with the operation of the latch-bar, consisting of a bow-spring between said swinging arm and said angular arm. 20

In testimony whereof I affix my signature in presence of two witnesses.

FRANK KARÁCSONYI.
